UNITED STATES PATENT OFFICE.

SAMUEL CLAUD BRAUD, OF NEW ORLEANS, LOUISIANA.

PACKER FOR STOCK FEED.

1,297,077.

Specification of Letters Patent. Patented Mar. 11, 1919.

Application filed April 19, 1918. Serial No. 229,585.

To all whom it may concern:

Be it known that I, SAMUEL C. BRAUD, a citizen of the United States, residing at New Orleans, in the parish of Orleans and 5 State of Louisiana, have invented certain new and useful Improvements in Packers for Stock Feed; and I do hereby declare the following to be a full, clear, and exact 10 description of the invention, such as will enable others skilled in the art to which it appertains to make and use the same.

The present invention relates to improvements in packers, and has for an object to provide an improved packer especially 15 adaptable for packing stock feed in sacks.

Another object of the present invention is to provide an improved packer of simple construction adapted to operate quickly and efficiently, and wherein the feed or other material to be packed may be readily loaded 20 into the machine, and the empty bags quickly put in place and after being filled quickly removed.

In the accompanying drawings forming a 25 part of this application, and in which similar reference symbols indicate corresponding parts in the several views:

Figure 1 is an end elevational view, with 30 parts shown in section of an improved packer constructed in accordance with the present invention.

Fig. 2 is a longitudinal vertical sectional view through the improved packer taken at 35 right angles to Fig. 1, and showing in dotted lines the advanced position of the plunger.

Fig. 3 is a top plan view of the improved hopper.

Fig. 4 is a horizontal sectional view taken on the line 4—4 in Fig. 1.

Fig. 5 is a plan view of the guide plate; and

Fig. 6 is a cross sectional view taken on the line 6—6 in Fig. 2.

Referring more particularly to the drawings, 1 designates a plunger of substantially 45 elliptical form as shown in Fig. 6, fitted to move through an elliptical casing 2 having a delivery mouth 3 about which is arranged a double series of staggered pins 4 for receiving the mouth of a sack or other receptacle 5.

The side walls of the casing 2 are extended 50 to form a hopper 6 having the inclined bottom 7 which directs the feed or other material delivered thereto into the casing 2;

there is a cut-away portion 8 provided at the upper end of this hopper 6 in order to enable the operator to look in beneath the plunger 1 and ascertain the amount and height of the material in the casing 2, and 60 to otherwise inspect the interior of the hopper and casing. The casing 2 and hopper 6 are supported in any suitable manner, preferably by braces 9 and 10, which are shown in Fig. 1 to diverge upwardly and be bolted 65 or otherwise fastened to appropriate supports.

A piston rod 11 driven by a piston which reciprocates in a cylinder 12 disposed above the casing 2, is threaded through a central 70 and threaded opening in the plunger 1 and locked therein by a lock nut 13. The piston in the cylinder 12 is preferably composed of three steel disks 14 spaced apart by cupped leather washers 15, the ends of which bear 75 against the cylinder walls. These disks 14 and washers 15 are, as shown in Fig. 2, fitted over the reduced end 16 of the piston rod 11 and held thereon by a nut 17. At its upper end the cylinder 12 is closed by a head 80 18 having a cylindrical flange 19 threaded to engage the threaded upper end of the cylinder 12. Brackets 20 are provided on the cylinder head 18 and cylindrical flange 19, and are adapted to receive bolts or other fastening means 21 by which the upper end of the cylinder may be held on a support.

In like manner the lower end of the cylinder 12 is closed by a head 22 formed with the cylindrical flange 23 threaded on the 90 lower end of the cylinder. This lower head carries a guide plate 25 having openings 26 in any suitable number therein, and carrying thereon a bracket 27 which enables the lower end of the cylinder to be fastened to some 95 object. The lower head 22 also carries a stuffing box 28 containing packing bag 29 surrounding the piston rod 11 and held in place by the gland 30. The heads of bolts 31 engage this gland 30 whereby to hold 100 same in place, such bolts or screws being attached or threaded into the cylinder head 22.

Guide rods 32 provided in suitable number, corresponding to the number of the 105 openings 26 in the plate 25, are slidingly fitted through said openings 26 and are attached to and movable with the plunger 1. For this purpose the plunger is preferably provided with small threaded openings to 110

receive the lower threaded ends 33 of such guide rods 32. The purpose of the guide rods is to steady the plunger 1 as it moves through the casing 2.

- 5 A compressed air pipe 34 from a suitable source of supply, is provided with the branches 35 and 36 leading respectively to the upper and lower ends of the cylinder, each of such branches including shut-off 10 cocks 37 and 38. A three-way or other valve 39 having operating means 40 actuated by hand or automatically, is provided to turn the compressed air alternately into the upper and lower ends of the cylinder 12 so as 15 to reciprocate the piston.

The operation of the invention is substantially as follows:

With the plunger 1 in the raised position shown in full lines in Fig. 2, the feed or 20 other material to be packed is dumped into the open upper end of the hopper 6 and is diverted by the inclined wall 7 into the casing 2 below such plunger. This material passes freely through the delivery mouth 3 25 of the casing 2 and into the receptacle 5, which has been previously affixed to the hooks or pins 4 in the manner shown. The operator may constantly observe the height 30 of this material, and when same rises to an appropriate level the delivery of further material may be cut off to prevent overflow of the hopper and casing.

The valve 39 is now moved to direct compressed air through the branch pipe 35 into 35 the upper end of the cylinder 12, the cocks 37 and 38 being normally open. This introduction of compressed air will drive the piston down, causing the plunger 1 to be also driven downwardly through the casing 2,

pushing before it the material, which it 40 packs into the bag or receptacle 5.

The plunger 1 may be driven to any lowered position required. Generally it will be found desirable to drive it to substantially the position shown in dotted lines in Fig. 2, 45 which will allow sufficient space above for the bringing of the mouth of the bag together for tying. When the bag is thus filled the valve 39 is turned to the position where it will allow the compressed air to 50 pass through the branch 36, at the same time closing the branch 35, and compressed air will therefore be put into communication with the lower part of the cylinder 12, where it will become effective to raise the piston and return the plunger 1 to the initial 55 position at the top of the casing 2. The sack 5 is now removed from the pins 4 and an empty sack substituted, whereupon the above described operations are repeated. 60

I claim:

In an apparatus having a casing, means whereby a receptacle to be filled may be supported with its mouth beneath the casing, and means traveling through the casing 65 for driving material therein into the receptacle, the combination of a hopper formed by extending the side walls of said casing, the hopper bottom being inclined whereby to direct the material into the casing and 70 through the delivery end of the latter, said hopper having a portion thereof cut away to enable the operator to look beneath said material driving means when the latter is in a retracted position, substantially as de- 75 scribed.

In testimony whereof, I affix my signature.

SAMUEL CLAUD BRAUD.
